UNITED STATES PATENT OFFICE.

HARRY G. WEBSTER, OF CHICAGO, ILLINOIS, ASSIGNOR TO MILO G. KELLOGG, OF CHICAGO, ILLINOIS.

TELEPHONE SYSTEM.

No. 921,318.

Specification of Letters Patent.

Patented May 11, 1909.

Application filed July 5, 1906. Serial No. 324,841.

To all whom it may concern:

Be it known that I, HARRY G. WEBSTER, residing in Chicago, county of Cook, and State of Illinois, have invented new and useful Improvements in Telephone Systems, of which the following is a specification.

My invention relates to telephone exchange systems and more particularly to the arrangement of the line circuits and associated apparatus by which the usual signals are transmitted and controlled by the subscriber and operator, and also to means for determining the busy or idle condition of the line.

15 The principal object of the invention is to provide a novel organization of circuits and apparatus for accomplishing these functions, which shall be simple in construction, efficient in operation and economical to manufacture.

In carrying out my invention, I employ, in association with the telephone line circuit, a novel controlling relay of the so-called double-acting type. This double-acting relay, which is along the line of those disclosed by me in prior applications, is arranged to cause the display of a line signal in response to a partial energization and to prevent such display when energized to a greater extent.

30 This is preferably brought about by arranging the relay contacts so that they will be moved through a portion of their maximum range in response to the partial energization of the relay, and through their entire range in response to the greater energization—the former to close the circuit of a signal lamp, and the latter to interrupt said circuit. In addition to these functions, the relay also varies the connections to its windings, and

40 the connection of the line limbs. In the cord circuit, I employ means for securing the greater energization of the relay during the application of ringing current to the line limbs as well as during the establishment of a connection. I also associate with the cord circuit a resistance or impedance which is included in circuit with a talking strand of the cord during the operation of securing a

45 busy test, but which is short circuited normally and after the called subscriber has responded.

The nature and objects of the invention will more fully appear from the following

detailed description, taken in connection with the accompanying drawing, and the scope of the invention will be particularly indicated in the appended claims.

In the accompanying drawing, which illustrates diagrammatically a telephone system constructed in accordance with a preferred form of my invention, A and A' indicate two substations which are connected to a central office by a suitable telephone line, and B and B' indicate two substations which are similarly connected by another line. The equipment at the substations, which may be of any preferred type, is here shown as comprising a call-bell b in series with a condenser e connected from the lower contact of the switch-hook h to ground. The switch-hook h is connected to one limb of the line, and its upper or alternate contact is connected with the opposite limb of the line through the receiver r and transmitter t, these instruments being included in bridge of the line when the switch-hook is raised.

At the central office, a relay 3 is provided for each line, having two windings, one of which is of low energizing capacity and is normally included in circuit with the battery C and the line limbs. The other winding is of greater energizing capacity and is normally disconnected from the line limbs, but has its terminals carried to the spring-jacks or switching terminals by which connection is established with the line for conversation. This relay is provided with an armature-contact 8 adapted to be actuated when the relay is energized by either or both windings, and with other contacts 6, 9 and 11 adapted to be actuated only when the relay is energized to its greater extent. The winding 7 of lower energizing capacity is preferably included in circuit with a battery C of relatively low voltage, whereas the winding 4 of greater energizing capacity is included in circuit with the battery D of relatively high voltage upon the establishment of a connection. When the subscriber A desires to initiate a call and removes his receiver from its switch-hook, current will flow from the active terminal of battery C, through winding 7, the anvil contact of armature 11, thence to the substations through limbs 2 and 1 of the line, and to the return or grounded side of the

battery C through armature 6 and its anvil contact. The battery C being of low voltage, and the winding 7 of low energizing capacity, the relay will be only sufficiently energized to cause the actuation of armature contact 8. Upon such actuation, current will flow from the battery C, through lamp 5, armature 8 and armature 9 to the opposite side of the battery, causing the illumination 10 of the lamp, which indicates a calling signal to the operator.

Upon the insertion of the connecting plug P into a jack 10 of the calling line, current will flow from battery D, through winding 15 20 of relay 16, strand 14 of the cord circuit, the sleeve contacts of the plug P and spring-jack 10, through winding 4 of relay 3 and thence through the tip contact pieces of the spring-jack and plug, strand 12 of the cord 25 circuit and winding 22 of the supervisory relay 16 to the return side of the battery. The battery D being of relatively high voltage, and the winding 4 of greater energizing capacity, the relay 3 is thus energized 30 to its greatest extent, causing the actuation of all of its armature contacts. The actuation of contacts 6 and 11 disconnects the line limbs from their normal connections to winding 7 and battery C and connects them 35 to the tip and sleeve contact pieces respectively of the spring jacks 10, and current then flows from battery D, through the line limbs to the substation. It is to be understood that the winding 4 of relay 3 is of 40 relatively high resistance and it will be seen that the current, which flows through windings 20 and 22 of supervisory relay 16, is of relatively small value until the circuit is established through the substation. Upon 45 the establishment of the circuit through the substation, relay 16, which is of the double-acting type, is completely actuated and the supervisory lamp 18 is not illuminated. After the insertion of the plug, the operator 50 actuates her listening-key $h-h$ in the usual manner and learns what subscriber is desired, it being assumed in the present case that subscriber B or B' is to be called. The operator tests in the usual manner by applying 55 the tip of her calling plug O to the sleeve or testing contact of the spring-jack 10. These spring-jacks, as will be seen, are normally insulated from the line limbs and from the central battery and ground, and no 60 current will flow. If, however, a connection exist at some other spring-jack than the one tested, current will flow, when a busy test is made, over a path which may be traced as follows: from battery D, either through 65 winding 21, strand 15 and sleeve contact of plug O of the connected cord circuit or through winding 20, strand 14 and sleeve contact of plug P; thence through the sleeve contact of the connected jack to the sleeve

contact of the tested jack, to the tip of the 65 cord with which the test is being made, through strand 13, ringing keys g^2 and g , through resistance 28 and through winding 22 of relay 17 to the return side of the battery. The resistance 28 is sufficiently great 70 to prevent an undue disturbance of the potential existing upon the terminal of the line tested if a conversation be in progress, and may be preferably in the form of impedance. After securing the busy test, the 75 operator releases her listening key which, by its upper or normally closed contact, completes a short circuit of resistance 28, thus preventing said resistance from interfering with the proper current flow to operate the supervisory relay 17.

Assuming that the line be idle, the calling plug O is inserted into the spark-jack 10 of the line desired; and in case the subscriber B be wanted, ringing key $g-g'$ is actuated. 85 The actuation of this ringing key completes a circuit for relay 3, which may be traced from battery D, through impedance i , contact 29, key lever g , strand 13, winding 4, strand 15 and key lever g' to ground, 90 causing the complete actuation of the relay contacts and thus connecting the two line limbs to the two terminals of the spring-jacks. At this time, a path for ringing current is provided from generator G, 95 through contact 30, key lever g , strand 13, armature 6 to limb 1 of the line and thence to ground through condenser c and bell b at the substation B. It is to be noted that during the actuation of the ringing key 100 $g-g'$, the generator G is connected in multiple with battery D, but that this connection is broken as soon as the ringing key is released. If subscriber B' be desired, ringing key g^2-g^3 is actuated, thus supplying 105 battery to relay 3 from battery D through impedance i and strand 15 of the cord circuit and thence through winding 4 and strand 13 to the ground or return side of the battery, thus energizing relay 3 to its 110 fullest extent as before and establishing a circuit for generator G through contact 32, key lever g^3 and strand 15 to limb 2 of the line and thence through the bell and condenser at substation B' to ground. Upon 115 the restoration of the ringing key, current from battery D will flow through winding 21 of relay 17, through strand 15, winding 4 of relay 3, strand 13 and winding 22 of relay 17. Winding 4 being of high resistance and of high energizing capacity, the armature contacts of relay 4 will be completely actuated; whereas the current through windings 21 and 22 of relay 17 will be only sufficient to cause the partial energization 120 of relay 17. This partial energization is sufficient only to cause the actuation of armature contact 23, thus completing a 125

circuit of battery D through supervisory lamp 19, contact 23, contact 25 and anvil 24 to the return side of the battery, causing the illumination of the lamp. At the same time, 5 the actuation of contacts 6 and 11 of relay 3 maintains the two limbs of the line in connection with the two strands of the cord circuit.

When the subscriber answers, thus closing 10 the circuit of the line limbs at the substation, an increased current will flow through windings 21 and 22 of relay 17, causing the complete actuation of its contacts. This will interrupt the circuit of lamp 19 at contact 25 and anvil 24, causing its extinguishment, and will cause the engagement of contacts 26 and 27, thus establishing a short circuit of resistance 28 separate from that controlled by the listening key *k*. The subscribers 15 being now in conversation, an actuation of listening key *k* will not result in bringing resistance 28 into serial relation with the strand 13, as when making a busy test, and consequently no interference with 20 conversation will result.

When either subscriber replaces his telephone, the current flowing through his associated supervisory relay 16 or 17 is reduced to that value resulting from the connection 30 existing through winding 4 of relay 3, and the supervisory relay contacts then assume their intermediate or partially actuated position, allowing the establishment of a circuit through lamp 18 or 19, as previously indicated. The illumination of both lamps constitutes the usual signal for disconnection. It will be observed that the spring-jacks of the line and the winding 4 of relay 3, with which they are connected, are normally disconnected 35 from the line limbs and from the central battery and ground; and that when a connection is established and the relay 3 thus completely energized, its winding 4 is brought into bridge of the two line limbs. 40 It will also be observed that the winding 7 of low energizing capacity is associated with a battery C of relatively low voltage; whereas as the battery D, by which the greater energization of the relay is secured, is of high 45 voltage, thus securing a very wide margin of operation for the partial and complete actuation of the relay contacts.

Obviously in carrying out my invention, batteries D and C need not be separate batteries, but the connection shown to battery C may be made at an intermediate point of battery D, and it will also be understood that the various grounds indicated may be replaced by a common return, and other 55 alterations and modifications may be made without departing from the spirit and scope of my invention. I therefore do not wish to be limited to the specific matter illustrated, but aim to cover by the terms of the 60

appended claims all such alterations and 65 modifications.

What I claim as new and desire to secure by Letters Patent of the United States is:—

1. A telephone system comprising a telephone line extending in two limbs from the substation to the central office, a two contact connection terminal therefor normally disconnected from the line limbs, a line signal, a controlling electromagnet, means under the control of the subscriber for energizing said magnet to cause the display of said line signal, and means under the control of the operator for energizing said magnet to cause the effacement of said signal and to cause the connection of the line limbs to said connection terminal contacts. 75 80

2. A telephone system comprising a telephone line extending in two limbs from a substation to a central office, a two contact connection terminal therefor normally disconnected from the line limbs, a line signal, a controlling electromagnet having a plurality of energizing windings, means under the control of the subscriber for supplying current to one of said windings to energize 90 said electromagnet, means responsive to such energization for displaying said signal, means under the control of the operator for supplying current to another of said windings to cause a different energization of said 95 electromagnet, and means responsive to said different energization to efface said signal and to connect said line limbs to the contacts of said connection terminal.

3. A telephone system comprising a telephone line extending in two limbs from a substation to a central office, a two contact connection terminal therefor normally disconnected from the line limbs, a line signal, a central source of current, a controlling electromagnet having a plurality of energizing windings, one included in a normally open circuit with said source of current and said line limbs, and another included in circuit with the connection terminal contacts, means under the control of the subscriber for closing said normally open circuit to energize said electromagnet, means for displaying said signal in response to such energization, means under the control of the operator for supplying current to said other energizing winding to cause a different energization of said electromagnet, and means responsive to said different energization to efface said signal and to connect the connection terminal contacts to said line limbs. 105 110 115

4. A telephone system comprising a telephone line extending in two limbs from a substation to a central office, a two contact connection terminal therefor normally disconnected from the line limbs, a line signal, a controlling electromagnet, means under the 125

- control of the subscriber for supplying current of low potential to energize said magnet, means responsive to such energization for displaying said signal, means under the control of the operator for supplying current of relatively high potential to energize said magnet to a greater extent, and means responsive to such greater energization for effacing said signal and connecting the line 10 limbs to said connection terminal contacts.
5. A telephone system comprising a telephone line extending in two limbs from a substation to a central office, a two contact connection terminal therefor normally disconnected from the line limbs, a line signal, a controlling electromagnet having a plurality of energizing windings, means under the control of the subscriber for supplying current of low potential to one of said windings to energize said electromagnet, means responsive to such energization to display said signal, means under the control of the operator for supplying current of relatively high potential to another of said windings 20 to cause a different energization of said magnet, and means responsive to said different energization to effect said signal and to connect said line limbs to said connection terminal contacts.
30. 6. A telephone system comprising a telephone line extending in two limbs from a substation to a central office, a two contact connection terminal therefor normally disconnected from the line limbs, a line signal, a controlling electro-magnet having a plurality of energizing windings, means under the control of the subscriber for supplying current of low potential to one of said windings to energize said electromagnet, means responsive to such energization to display said signal, means under the control of the operator for supplying current of relatively high potential to another of said windings 40 to cause a greater energization of said magnet, and means responsive to said different energization to effect said signal and to connect said line limbs to said connection terminal contacts.
45. 7. A telephone system comprising a telephone line extending in two limbs from a substation to a central office, a two contact connection terminal therefor normally disconnected from the line limbs, a line signal, a relatively low potential source of current, a controlling electromagnet having a plurality of energizing windings, one included in a normally open circuit with said low potential current source and said line limbs and another included in circuit with the connection 55 terminal contacts, means under the control of the subscriber for closing said normally open circuit to energize said electromagnet, means for displaying said signal in response to such energization, means

under the control of the operator for supplying current of relatively high potential to said other energizing winding to cause a different energization of said electromagnet, and means responsive to said different energization to efface said signal and to connect 70 the connection terminal contacts to said line limbs.

8. A telephone system comprising a telephone line extending in two limbs from a substation to a central office, a two contact connection terminal therefor normally disconnected from the line limbs, a line signal, a relatively low potential source of current, a controlling electromagnet having a plurality of energizing windings, one included in a normally open circuit with said low potential current source and said line limbs and another included in circuit with the connection terminal contacts, means under the control of the subscriber for closing said 85 normally open circuit to energize said electromagnet, means for displaying said signal in response to such energization, a link-circuit and connecting plug for establishing connection with said connection terminal, a high potential source of current in bridge 90 of the link-circuit strands whereby, upon the insertion of said plug into said terminal, said electromagnet will be energized through said other energizing winding, and means responsive to said latter energization for effacing said signal and connecting said connection terminal contacts to said line limbs.

9. A telephone exchange system comprising a telephone line extending in two limbs from a substation to the exchange, a signal, a relay for causing the display and effacement of said signal, means for causing the operation of said relay to display said signal by closing a circuit over the limbs of said 100 line in series, a source of ringing current, and one and the same means for temporarily applying ringing current to said line and causing the signal effacing operation of said relay.

10. A telephone exchange system comprising a telephone line connecting a substation with the exchange, a signal, a relay for controlling the display and effacement of said signal, a spring-jack for said line normally disconnected therefrom, means for causing the operation of said relay to display said signal by closing the circuit over said line, a source of ringing current, a ringing key, means for connecting said ringing key to 115 said jack, and means responsive to the operation of said ringing key for applying ringing current to the line and causing the signal effacing operation of said relay.

11. A telephone exchange system comprising a telephone line extending in two limbs from a substation to the exchange, a two-contact connection terminal therefor nor-

mally disconnected from the line limbs, a signal, a relay for causing the display and effacement of said signal, means under the control of the subscriber for energizing said relay to cause the display of said signal, a source of ringing current, means under the control of the operator for temporarily applying ringing current to said line and caus-

ing the operation of said relay to efface said signal.

In witness whereof, I hereunto subscribe my name this 30th day of June 1906.

HARRY G. WEBSTER.

Witnesses:

GEO. E. MUELLER,

A. H. DYSON.

It is hereby certified that in Letters Patent No. 921,318, granted May 11, 1909, upon the application of Harry G. Webster, of Chicago, Illinois, for an improvement in "Telephone Systems," errors appear in the printed specification requiring correction, as follows: In line 83, page 2, the compound word "spark-jack" should read *spring-jack*, and in lines 27 and 46, page 4, the word "effect" should read *efface*; and that the said Letters Patent should be read with these corrections therein that the same may conform to the record of the case in the Patent Office.

Signed and sealed this 22d day of June, A. D., 1909.

[SEAL.]

C. C. BILLINGS,

Acting Commissioner of Patents.
